ABSTRACT OF THE DISCLOSURE

In a heel anchor binding, a retaining jaw intended to be folded over the edge of the boot of the skier to block the same against a stop integral with the ski, a locking device for locking the jaw in its folded position, a pedal movable between a high and a low position by the heel of the boot of the skier when the same puts on the ski and a kinematic link between the jaw and the pedal arranged in such a way as to fold over the jaw when the pedal is brought by the skier into its upper position, this link premitting the relative movement of the pedal and of the jaw at the end of their respective paths of travel.

There are already known rear ski or anchor bindings without a cable which act by bearing a jaw against the heel of the sole of the boot which comprise additionally, in order to make possible the automatic wear of these bindings, a pedal urged by the lowering of the boot and having for its purpose on the one hand to bring the jaw in operative position and on the other hand to reset a locking device.

In known bindings of this type, the movement of the pedal is related by a precise and definite kinematic law to that of the jaw: this rule has been applied in bindings having a jaw and a pedal forming a monolithic piece if one disregards devices which permit to position the jaw in function of the thickness of the sole of the ski boot and on the other hand of devices in which the jaw and the pedal are mutually connected by pivots, whether these be direct pivots or those obtained by means of suitable intermediate pins.

With these known bindings, a position given to one of the elements, the jaw or the pedal, necessarily implies a single corresponding position of the other. This characteristic has not been found advantageous in use in particular when a deposit of snow or ice accumulates on the boot, between the boot and ski, or between the pedal and the ski, such a deposit limiting the possible movement of the pedal and consequently that of the jaw which no longer can exert on the heel a sufficient stress such that the cooperation between the binding and the boot becomes relatively precarious.

The present invention precisely has for its object to remedy this drawback and accordingly seeks to provide a rear ski or anchor binding comprising a jaw intended to be folded over on the edge of the heel of the ski boot to ensure its blocking against a stop integral with the ski, means for locking the jaw in folded position, a pedal adapted to be moved from a higher to a lower position by the heel of the skier's boot when the same puts on his ski and with a kinematic linkage between the jaw and the pedal arranged in such a way as to occasion said folding over of the jaw when the pedal is placed into its low position by the skier, this new binding being further characterised by the fact that this linkage makes possible the relative movement of the pedal and of the jaw at the end of the path of travel of these elements.

In known bindings, the folding over of the jaw on the heel of the skier's boot takes place in two steps:

2

An approach of the jaw toward the heel,
A placing under tension and a locking.

The step of placing the jaw under tension takes place during a greater or smaller movement of the jaw in proportion of the degree of flexibility of the elastic locking means of the binding.

The pedal serves to cause the approach of the jaw by bringing it in a position such that its placing under tension can begin and thereafter has no functional role: if this pedal is connected to the jaw in its movements, it must be able to move therewith also during the elementary movement required by the placing under tension. It will be understood then that as soon as a deposit of snow forms which will prevent this terminal movement of the pedal this will also prevent the placing under tension of the jaw.

To avoid this disadvantage, the bindings now known have a housing permitting the retraction of the pedal and which is located under the support level of the heel of the boot at a distance from this level at least equal to the distance which the jaw must still travel in order to be placed under tension starting from the moment when it has been brought sufficiently near the heel of the boot to lock.

The arrangement provided in the present invention makes possible the elimination of this housing so that at the beginning of the step of approach of the jaw, the opening pedal-jaw can be as great as desired which permits to avoid all encounter between the jaw and the upper part of the ski boot during the performance of this first step.

With known bindings, such an opening, necessarily greater than the thickness of the heel, could only be made by increasing proportionately the depths of the housing intended for the pedal. It is seen immediately that this is only possible at a price of increasing the dimensions of the binding assembly which becomes naturally more costly than necessary and the aesthetic appearance of which is thereby marred.

It should furthermore be noted that the greater the opening separating the jaw and the pedal the greater the movement of the jaw corresponding to the first step of folding over which naturally limits the thickness of snow and ice which can deposit between the boot and the ski without this thickness influencing the correct tightening of the jaw.

The accompanying drawings represent by way of non-limiting example different embodiments of the present invention:

FIGURES 1 to 3 are each longitudinal cross-sectional views of the same embodiment in three different operating positions.

FIGURES 4 to 6 show more schematically three different views of another binding according to the invention.

FIGURES 7 to 9 show schematically a third embodiment of the invention in its three functioning positions.

FIGURES 10 to 16 show schematically in elevation seven other modifications of the embodiments shown in FIGURES 7 to 9.

FIGURES 17 and 18 are schematic elevational views of a fourth embodiment of the device of the invention.

In the embodiment shown in FIGURES 1 to 3, the binding according to the invention comprises a base plate 1 secured to the ski 2 by means of screws 3, the left hand extremity of which has a rib 4 forming a stop on which will bear the heel of the skier's boot and on which is mounted by means of slides 1a, a sole 6 longitudinally slotted at 7 and the axial position of which on plate 1 can be adjusted by tightening a screw 8a on a bolt 8b passing through slot 7 and integral with said plate 1.

On this sole 6 is slidably mounted a casing 9 connected to the sole by a compression spring 10 between a projection 6a thereof and an element 11 of casing 9 forming a cam for a stop 12 for locking the binding and mounted on the left hand extremity of a rod 13. This rod is engaged by its threaded part 13a in a passage provided in the common part 14a of a spur 14 the parallel branches of which are pivoted on a shaft 15 transversal to the ski and which is carried by a lever 16a pivoted at 17 on the casing, the shaft 15 being eccentric by a suitable distance relative to shaft 17.

Rod 13 is elastically connected to spur 14 by means of a spring 17 under compression between part 14a of the spur and a tightening head 18 constituted by a screw in mesh with the thread 13a of the rod and the axial position of which can be adjusted in function of the compression to be given to spring 17.

As shown on the drawing (FIGURES 1 and 2), stop 12 can have two positions: one upright in which it is maintained by contact with the upper face of cam 11, and the other lowered, in which it is in contact with the inclined left surface of this cam under the urging of the rounded lower edge of beak 19 and against spring 17 which is under compression.

When in upright position, stop 12 takes care of the angular locking of the beak which is secured at the extremity of a lever 20 pivoted around a shaft 21 and which bears on its left hand face two legs 22 between which is pivoted a threaded rod 23 the upper extremity of which is slotted by the transversal slot 23a intended for engagement by a tool, screw-driver or simply the edge of a coin. On this rod 23 is engaged a member 24 constituting the jaw by which the binding according to the invention is able to take hold of the heel of ski boot 5.

The adjustment of the position of jaw 24 on rod 23 can therefore be effected in a particularly precise and simple manner by pivoting this rod.

The lowering of jaw 24 on ski boot heel 5 takes place as in known bindings by pressure of the heel on a pedal or lever 25 of the binding and on which the skier steps with his boot. This pedal which is constituted by an open L-shaped metallic plate is also pivoted around shaft 21 and is engaged by one of its parts through a slot 26a in leg 26 of lever 20 which carries the jaw.

Plate 25 is thus free to move angularly without moving lever 20 and jaw 24 rigid therewith as long as it does not come into contact with the extreme lower or higher part of the edges defining slot 26a.

For the ski-bound position of the anchor (FIGURE 1) plate 25 is thus able to assume any angular position between the two limits given by the upper edge and the lower edge of slot 26a without changing the position of jaw 24 which remains the same: it is thus seen that even if a mass of snow having a thickness corresponding substantially to the length of slot 26a were to deposit on the part of the anchor disposed between rib 4 and the left hand extremity of sole 6, this mass would not prevent the complete clamping of the anchor since it would only slightly raise pedal 25 relative to the position it occupies in the figure.

In released position, the binding according to the invention is as shown in FIGURE 2. It is seen that stop 12 is in a collapsed position in which it is maintained by the lower rounded part of beak 19 against the urging of spring 17 which is taut. Lever 16 is folded over casing 9.

When the skier steps on the ski in order to bind the anchor on the heel of the boot, he presses with his heel on pedal 25 in the direction of arrow F (FIGURE 2) and thereby causes lever 20 bearing jaw 24 to tip with jaw 24 folding over in the direction of the upper edge of the heel, or of a groove formed at the heel welt in conventional ski boots and used to receive the spring loaded heel cable of other types of binders. Beak 19 integral with lever 20 also moves in the direction F: at

the moment when jaw 24 is about to touch heel 5, beak 19 is in an angular position such that it is in contact with stop 12 only by the terminal portion 19a of its rounded section so that this stop then is able to ascend into locking position (FIGURE 1) under the urging of spring 17 which relaxes by contact with the inclined left facette of cam 11. This relaxation of spring 17 causes also a slight counter-clockwise movement of beak 19 and of jaw 14 corresponding to the distance necessary for placing the jaw under tension.

It is thus stop 12 which maintains jaw 24 in locked position.

The anchor shown opens automatically as soon as a given effort greater than that necessary for compressing spring 17 acts in clockwise direction on jaw 24. The intensity of this effort, which can for example be occasioned by the fall of the skier, is adjustable by a greater or lesser screwing in of nut 18.

In this case, beak 19 acts on stop 12 driving it to the left by compression of spring 17, the opening of the anchor taking place when this stop is brought to slide on the inclined edge of cam 11.

Similarly this anchor binding can also be opened by direct action of the skier on lever 16 in tipping the latter in a position shown in FIGURE 3, which has for result to lower stop 12 and to thus free beak 19.

In a second embodiment of the invention which is shown schematically in FIGURES 4 to 6, the pedal is formed by the left hand side extremity 27 of a lever 28 pivoted on a shaft 29 integral with a casing which is not shown. This casing can, as before, be mounted flexibly and slidably on the ski.

Lever 28 carries a shaft 30 mounted near pedal 27 and engaged in a slot 31 cut in the lower part of an inverted L-shaped piece 32 the shortest branch of which, 33, forms the securing jaw of the binding. This jaw is represented as being fixed, but it is evident that it can also be constituted by a distinct piece mounted on threaded rods integral with piece 32 which would permit to adjust its vertical position in the manner described on FIGURES 1 to 3.

This piece 32 is additionally connected to a shaft 34, secured to the casing (not shown) of the anchor, parallel to shaft 29, by means of a small rod 35 to which it is pivoted at 36.

At its lower part, opposite to pedal 27, piece 32 additionally carries a beak 32a, the extremity of which can for example be provided with a roller by means of which it is in permanent contact with the edge of cam 37 which is pivoted around shaft 34, previously mentioned, and also subjected to the action of spring 38 tending to urge it against beak 32a of piece 32. This cam 37 has an L-shaped profile.

In the released position of the heel anchor, lever 28 is slightly upwardly inclined and beak 32a bears against the left hand side of cam 37, the spring 38 being then compressed to the maximum. The extent of compression of this spring naturally can be adjusted by any suitable means which need not be shown.

When the skier steps on the ski he applies his heel on pedal 27 and causes accordingly the tipping of lever 28 and of the entire heel anchor in direction F. During this movement, beak 32a slides on the edge of cam 37 and nears its rounded point 37a. It is starting from the moment when it passes this point and moves in contact with the lower edge of cam 37 that takes place the locking of the anchor. This exact relative position of beak 32a and cam 37 for which the locking is complete is naturally in function of the respective shape of these two elements.

The opening of the heel anchor described can also be obtained by exerting on jaw 33 an effort tending to move away from the surface of the ski against spring 38.

FIGURES 5 and 6 show the functioning of the heel anchor when the surface of the ski is covered by a layer 75 of snow having thickness e.

When pedal 27 comes into contact with the snow, the pivoting of lever 28 terminates (FIGURE 5) when the tightening of jaw 33 is not terminated. It is spring 38 which furnishes, as before, the effort necessary for the last displacement of jaw 33. This displacement is still possible since piece 32 and lever 28 are capable of a slight relative movement in amplitude corresponding to the length of slot 31. Piece 32 at the end of this movement is in the positon shown on FIGURE 6.

Naturally this type of anchor will also have a manual opening device.

The heel anchor according to the third embodiment is essentially formed by two levers 40 and 41 pivoted around a common shaft 42 and by an elastic locking system comprising a ball 43 slidably mounted in a cylindrical passage 44 provided in case 45 of the heel anchor, shown schematically in the drawing, this ball being subject to the urging of an adjustable spring 46.

Ball 43 is constantly applied by this spring against the edge of a cam 47 formed in the right arm of lever 41, the left arm of which 41a, constitutes the jaw of the anchor. This jaw can also be independent of lever 41 and be secured thereto by any suitable means permitting to modify the relative position thereof. The section of the cam terminates near its lower section by a type of nick in which enters ball 43 in bound position of the anchor.

Jaw 41a which is driven into this position by the action of the skier's heel on the lever 40, the left arm of which 40a forms an actuating pedal and the right arm of which, 40b, substantially shorter than the left arm, constitutes the element by means of which lever 40 acts on lever 41 to cause the tipping in direction F.

FIGURES 8 and 9 show the behaviour of the anchor when the ski is covered by a layer of hard snow of thickness e . The anchor is actually so proportioned that when pedal 40a enters into contact with this layer (FIGURE 8), the tipping movement of lever 41 is not completely terminated.

It is again the locking mechanism 42 to 45, or any similar device, which makes possible the final positioning of this lever in locked position, in cooperation with cam 47 the part immediately preceding the terminal nick previously mentioned has a section such that ball 43 rolls on this section in direction of this nick under the urging of spring 46. This lever 41 then has the position corresponding to that of FIGURE 9. It is seen that it is separated from lever 40 by a distance f corresponding substantially to the thickness e of the snow on which bears lever 40.

In a modification, the shape of levers 40 and 41 can be slightly different from that shown in FIGURES 7 to 9 in order to permit the adjustment of the maximum spacing of these levers in order to adapt the anchor to boots having heels of different thicknesses (FIGURES 10 to 12).

Naturally, the locking device 43 to 46, or any other similar device, will also be provided even though it is not shown: it will be arranged in such a way as to exert its action on a suitable part of the lever forming the jaw.

The pivoting axes of the two levers can coincide (FIGURE 10) or, on the contrary, can be distinct (FIGURES 11 and 12).

Finally, one of them can be connected to the other by means of a flexible member such as a spring as in FIGURE 12.

In another modification (FIGURE 13), the anchor can comprise two levers 47 and 48 pivoted around the same shaft 49, the left arm of lever 47 constituting the gripping jaw and its right hand extremity being solicited by a locking mechanism, for example of the type formed by elements 43 to 46 of FIGURE 7. Lever 48 assumes here the shape of a C, the lower horizontal branch of which forms the actuating pedal, the upper one carry-

ing a rod 50 slidably axially against the urging of a spring 51, and the assembly constituted by this rod and this spring forming a pusher by means of which lever 48 is able to drive lever 47 when it is urged in the direction F by the heel of a boot acting on the pedal.

In the modification according to FIGURE 14, the heel anchor according to the invention comprises a lever 52 pivoted at 53 and forming a jaw at its left hand part and a pedal 54 constituted by the horizontal branch of a L-shaped binding iron slidably mounted in a passage 55 of lever 52. The relative axial position of this binding iron is determined on the one hand by support head 56 and on the other hand by a spring 57 under tension between lever 52 and pedal 54. The locking of lever 52 is possible by pushing on its right hand extremity.

In the modification shown in FIGURE 15, the heel anchor is formed by a L-shaped lever, 58, pivoted at 59 and the horizontal branch of which 58a forms the gripping jaw of the anchor, the lower extremity of the vertical branch of lever 58 forming a beak 58b on which bears an elastic blade 60, in the shape of a C.

This blade is engaged by its vertical part through a passage 61 provided in lever 58 and bears by its upper horizontal branch on the upper edge of jaw 58a: it is the lower horizontal branch of blade 60 which forms the actuating pedal of the anchor, this pedal thus being able to bend when it encounters an obstacle such as a layer of snow, without causing the stopping of jaw 58a.

The modification shown in FIGURE 16 is an extrapolation of that shown in FIGURE 15. As is the latter, the anchor comprises a jaw constituted by the horizontal branch of a L-shaped lever, 62, pivoted around a shaft 63, but the pedal has been secured to the lower extremity of the vertical branch. This pedal is formed by the left arm of lever 64 pivoted at 65 on lever 62 and bearing on the dorsal part thereof by its right arm.

Naturally, this leaning stops as soon as the pedal is stopped in its path, such as for example by a layer of snow on the ski. The locking of lever 62 in gripping position can be effected by any suitable means as is the case for the other previously mentioned modifications.

In the last modification shown (FIGURES 17 and 18), the heel anchor according to the invention is formed by two levers facing one another 66 and 67, pivoted at 68 and the left part of which forms respectively the jaw and the pedal. The right extremities of these levers are in contact with the opposed edges of a tipping lever 69 pivoted at 70 which they grip and which constitutes the kinematic linking element for levers 66 and 67. Tipping lever 69 is naturally subject to the action of elastically operating locking members capable of bringing lever 66 in tightening position (illustrated in dotted lines in FIGURE 17) at the instant when pedal 67 has been stopped in its path by an obstacle (position corresponding to the fastening elements illustrated in full lines in FIGURE 17).

In a modification, not shown, the locking members of this anchor could act directly on lever 66.

In another embodiment, also not shown, the anchor could be provided with locking members acting on lever 66 and on tipping lever 69.

It should also be noted that tipping lever 69 can have a shape designed in order to permit the control of the law of variation of the opening pedal-jaw along the movement of these two elements.

The invention is naturally not limited to what has been represented or described: in particular the inventive principles constituting the basis thereof can be carried out with an anchor the movement of whose jaw or of whose pedal would be different from those mentioned.

Similarly it would be possible to apply these same principles to an anchor the pedal-jaw interaction means of which are different: it could be direct or indirect by means of any suitable piece, of an elastic means, of a

system for adjusting the opening pedal-jaw by means of a screw or a cog, etc.

The locking and moving device for the anchor can be any whatever.

From the foregoing it will be appreciated that as devised the new type of heel anchoring ski binder is highly efficient in use, simple to install and to operate, and economically from the stand point of manufacture.

It will be understood by those skilled in this art that the present heel anchor is adapted for mounting on a ski a boot length behind a conventional toe abutment forming no part of the present invention.

What is claimed is:

1. In a ski binder for releasably securing a ski boot to a ski, a heel anchor comprising a plate adjustably and slidably mounted on said ski, said plate having at one end thereof a stop; a housing slidably mounted on said plate and normally spring-urged forwardly, ski boot heel holding down means pivoted on said housing and adapted to be lowered against the heel of said boot for clamping said heel against said stop; means for locking said holding down means in lowered position; a pedal below said means and movable by the heel of said ski boot between a raised and a lowered position, a kinematic link between said holding down means and said pedal for lowering said holding down means when said pedal is lowered by said heel, means associated with said link and said pedal to limit pivoted movement of said holding down means relative to said pedal.

2. Heel anchor according to claim 1, wherein said pedal has a fixed axis and said holding down means are articulated about said fixed axis; said holding down means including an elongated vertical slot receiving said axis, said slot having a length defining the extent of relative movement between said pedal and said holding down means.

3. Heel anchor according to claim 1, wherein said locking means consist of a beak integral with said jaw, a retractable stop operatively associated with said beak to prevent the same from moving when said jaw is in lowered position, an elastic member urging said stop in locked position, a fixed cam for retracting said stop when said elastic member is taut and for bringing it in operative positive when said member is relaxed, said beak bringing said stop into retracted position and maintaining it therein against said elastic member when said jaw is subject to a predetermined effort opposing the maintenance of said jaw in lowered position.

4. Heel anchor according to claim 3, wherein said stop is integral with at least one longitudinally slidable rod and said elastic member consists of a spiral spring surrounding said rod and bearing on one end thereof, said housing having a locking lever pivoted thereon said lever having pivoted thereon a longitudinal eccentrically disposed rod, said other end of said spring bearing on at least a part of said rod.

5. Heel anchor according to claim 4, having a cam controlling the positioning of said stop, said spring being taut between said cam and a part of said plate.

6. Heel anchor according to claim 1, wherein said pedal consists of the extremity of a first lever pivoted in a plane longitudinal with said ski, and said holding down means include a jaw consisting of the bent extremity of at least a second lever pivoted on said first lever; a stop member on said second lever, one of said levers having a slot and the other having a pin slidably mounted in said slot, said slot having a length determining the possible relative position of said pedal and said jaw, a linking rod pivotably connecting said second lever to said housing, said rod being swingable in a plane parallel to said second lever; said

locking means comprising an L-shaped cam having two branches, said linking rod connecting one of said branches to said housing, the other of said branches having an outer edge, spring means tending to maintain said edge in contact with said stop member on said second lever when said jaw is in lowered position, in order to ensure locking thereof, said stop member on said second lever being in contact with said other branch of said cam for the raised position of said jaw.

10 7. Heel anchor according to claim 1, wherein said pedal and said jaw are each constituted by one of the arms of a double lever in mutual contact by their other arm, said other arm of said lever forming said jaw forming a cam for a headed support, a cam having a recess therein, a spring urged headed support engaged in said recess for locking said jaw in lowered position.

8. Heel anchor according to claim 7 having an adjustable stop integral with one of said levers for making contact between said second arm of said two levers.

9. Heel anchor according to claim 7, wherein said levers are elastically connected by their second arms.

10 10. Heel anchor according to claim 1, wherein said pedal and said jaw are each constituted by one of the arms of a double lever, said arm forming said jaw being substantially horizontal and solicited by said locking means, said arm forming said pedal having the shape of a C having two horizontal branches, one of said branches forming said pedal proper, and the other extending above said jaw, and an intermediate elastic link for making said other branch bear on said jaw.

11. Heel anchor according to claim 1, wherein said jaw consists of one arm of a double lever, the other arm thereof being solicited by said locking means, a L-shaped piece having a horizontal branch forming said pedal and having a vertical branch, said vertical branch being connected to said jaw, said pedal being vertically connected to said arm by means of a spring taut between said pedal and said jaw, and by a headed support secured at the upper extremity of said vertical branch, above said jaw.

12. Heel anchor according to claim 1, having a L-shaped lever having two interconnected branches, said jaw being constituted by one of said branches, and a C-shaped elastic blade having a lower horizontal branch, said branch passing through said jaw, said other branch of said elastic blade bearing on the upper part of said jaw.

13. Heel anchor according to claim 1, having a L-shaped lever having two branches, one of said branches forming said jaw, a double lever pivoted at the extremity of said second branch of said L-shaped lever and forming said pedal, the second arm of said double lever being in contact with said second branch of said L-shaped lever, from the side opposite said first branch.

14. Heel anchor according to claim 1, having two levers pivoted on a same shaft, said jaw and said pedal consisting of one of the arms of said levers, said levers having another arm, a cam consisting of a locking lever disposed between said two levers and connecting said jaw and said pedal.
